CLAIM

The ornamental design for a slotted hanger, as shown and described.

DESCRIPTION

FIG. 1 is an oblique view of the slotted hanger of the instant invention.

FIG. 2 is an elevation view of one side of the slotted hanger as shown in FIG. 1. The reverse side view is the mirror image thereof.

FIG. 3 is an elevation view of the left end of the slotted hanger as shown in FIG. 2.

FIG. 4 is an elevation view of the right end of the slotted hanger shown in FIG. 2.

FIG. 5 is a top view of the slotted hanger shown in FIG. 2; and,

FIG. 6 is a bottom view of the slotted hanger shown in FIG. 2.
